UNITED STATES PATENT OFFICE.

JAMES A. C. HIETT, OF BAKERSFIELD, CALIFORNIA.

AUTOMATIC GRAMOPHONE STOP OR BRAKE.

1,123,125.

Specification of Letters Patent.

Patented Dec. 29, 1914.

Application filed January 31, 1913. Serial No. 745,462.

To all whom it may concern:

Be it known that I, JAMES A. C. HIETT, a citizen of the United States, residing at Bakersfield, in the county of Kern, State of California, have invented certain new and useful Improvements in Automatic Gramophone Stops or Brakes; and I do hereby declare the following to be a full, clear, and exact description of the invention, such as will enable others skilled in the art to which it appertains to make and use the same.

This invention has special reference to brakes or stops for gramophones and the like, designed for automatically bringing the turn table of the machine to a state of rest immediately upon the completion of the reproduction or to permit manual stopping of the machine at any desired time.

The essential object of the invention is evolved in the provision of a simple and novel device of the character aforementioned including a trip actuated brake or stop adapted to stop and hold the turn table by frictional contact with the peripheral edge of the latter, while engaging means are provided for attachment to the reproducer carrying arm to release said trip operating brake upon the completion of the reproduction, the device being designed for use with machines slightly differing in construction.

With the above and other objects in view, the invention resides more particularly in the peculiar combinations and arrangements of parts which will be partly illustrated as a preferred embodiment in the accompanying drawings and described in the specification, although the invention is protected for all desirable changes and uses within the scope of the invention as claimed.

Figure 1 is a top plan view of a fragmentary portion of a gramophone with the invention applied thereto. Fig. 2 is a side elevation with the parts in the position shown in Fig. 1. Fig. 3 is a plan view showing the brake in a tripped position so as to bring the turn table to a stop, as well as the working parts of the gramophone. Fig. 4 is a detail sectional view of the reproducer carrying arm or sounding arm with the trip carried thereby in elevation. Fig. 5 is a detail view of a modified form of trip. Fig. 6 is a similar view of a further modified form of trip.

In illustrating the preferred embodiment of the invention, there is shown a gramo-

phone which includes the usual casing 10 containing a suitable motor for operating the turn table 11 which is adapted to carry the record disk 12 in the usual manner. The reproducer carrying arm or sounding arm 13 is supported in the usual manner at one side of the casing for pivotal movement to permit its reproducer 14 to traverse the disk record in traveling from the edge to the center of the latter during the reproduction action or to be shifted in the opposite direction after the completion of the reproduction, for another operation.

The usual manner of bringing the machine to a state of rest is by the provision of a mechanism connected with the motor but the present device operates against the edge of the turn table or metallic rim 15 thereof and embodies a base 16 which is secured to the top portion of the casing and has attached thereto near one end in a vertically slotted stud 17, a leaf spring 18 which is arranged edgewise. The free end of the spring carries a rubber or other soft flexible engaging seat or shoe 19 which under the action of the spring is normally held in frictional contact or engagement with the edge or rim of the turn table to bring the latter to a state of rest by overcoming the power of the motor.

The tripping or releasing mechanism embodies an arm 20 which is pivoted to the base 16 at its inner edge and at its end removed from the end to which the spring is anchored and said arm is offset upwardly and connected pivotally to the spring near the free end of the latter by a link 21, preferably of wire. In order to hold the shoe carried by the spring disengaged from the turn table, the arm is swung on its pivot until it is in alignment with the link and slightly beyond the dead center in a direction toward the anchored end of the spring, where it is held by engagement with an angular stop 22 which is also carried by the base.

As aforementioned, the arm is offset upwardly, this being for the purpose of passing over the attaching means of the angular stop and for elevating the arm whereby an angular engaging member 23 slidably carried on the free end of the arm will be in convenient position to be tripped. The engaging member 23 is slidably or adjustably carried by the arm for use with different sized records as well as records having varying

numbers of spirally arranged record grooves and for this purpose, the engaging member is provided with a longitudinal slot 24 permitting it to be adjusted on a clamping screw 5 and nut 25 carried by the arm, the free end of the arm being bent upwardly as shown at 26 to render the attachment more rigid.

The tripping means for use with a gramophone is in the form of a band 27 which is clamped on the reproducer carrying or sounding arm as by means of a clamping screw 28 when one extremity of the band is longer than the other to provide a trip arm 15 29 which is adapted to abut the angular end of the engaging member for releasing the spring by moving the trip arm 20 to pass the dead center and consequently permitting the spring to move to a braking position. 20 The trip arm 29 is reinforced by a section of wire 30 held against the same by a nut 31 mounted on the clamping screw; it being observed that the band is formed of a strip of metal.

25 As a modified form of tripping means, I provide an angular arm 32 the screw shank 33 of which is adapted to be threaded into the reproducer carrying or sounding arm so as to depend from the latter in a similar 30 manner as the trip arm 29, and then held by a set nut 34. The arm however may be formed straight as shown at 35 in Fig. 6, in contradistinction to the angular formation thereof as shown in Fig. 5 and as just described. It will thus appear that when the 35 reproducer carrying or sounding arm has moved to the innermost grooves of the record, the trip arm will release the braking spring and bring the turn table and machine

to a stop automatically upon the completion of the reproduction, thus preventing the continued rotation of the disk and mutilation of the latter by the reproducing needle, as now generally occurs. It will also be apparent that the engaging member may be tripped at any particular time to operate the brake or stopping mechanism before the completion of the reproduction.

I claim:

A braking mechanism for a machine having a rotatable element and a swinging arm, said braking mechanism including a resilient arm anchored at one end, a brake shoe carried at the free end of the resilient arm and adapted to be normally forced into braking position relative to the rotatable element of the machine by the resilient arm, a pivoted arm adjacent said resilient arm, a link connection between the resilient arm and the pivoted arm and adapted when said pivoted arm is moved in one direction to draw the resilient arm and the brake shoe away from the rotatable element of the machine, a stop for limiting the movement of the pivoted arm in one direction, an adjustable contact bar carried by the pivoted arm, and a tripping member carried by the swinging arm of the machine adapted to contact with the contact bar to shift the pivoted arm and permit the brake shoe to be moved to braking position relative to the rotatable element of the machine.

In testimony whereof, I affix my signature, in the presence of two witnesses.

JAMES A. C. HIETT.
